(57) **CLAIM**

The ornamental design for an out door unit for air conditioner, as shown and described.

DESCRIPTION

FIG. 1 is a perspective view of an out door unit for air conditioner showing our new design;

FIG. 2 is a front view thereof;

FIG. 3 is a rear view thereof;

FIG. 4 is a plan view thereof;

FIG. 5 is a bottom view thereof;

FIG. 6 is a left side view thereof; and,

FIG. 7 is a right side view thereof.

The broken lines depict portions of the out door unit for air conditioner that form no part of claimed design.
